UNITED STATES PATENT OFFICE.

FRANZ K. KRAG, OF CHICAGO, ILLINOIS.

DRILLING MACHINE.

Application filed October 3, 1923. Serial No. 666,320.

My invention relates generally to improvements in drilling machines, but relates more particularly to improvements in the so-called drill press type of drilling machine.

5 The general object of my invention is to improve the construction and operation of drill presses.

Another object of my invention is to provide means whereby a wider range of work can be practically and successfully performed.

Again I aim to provide a drill press construction wherewith very fine and accurate work such for example as providing pilot 15 drillings or "spots" can be made quickly and easily and also accurately placed holes for other purposes, all by means of an ordinary drill press, thus saving much time and expense and obviating the necessity of having 20 a special machine for such work.

My invention consists generally in a drilling machine and in an attachment therefor comprising such an arrangement, form, and construction that the above named objects 25 together with others that will appear hereinafter are attainable. My invention will be more readily understood by reference to the accompanying drawings which illustrate what I consider, at the present time, to be 30 the preferred embodiment thereof.

In said drawings:

Fig. 1 is a side elevation of a portion of a drilling machine embodying my invention, part thereof being broken away better to 35 disclose the interior construction.

Fig. 2 is a perspective view of the drill guide member detached from the machine; and

Fig. 3 is a view substantially on the line 40 3—3 of Fig. 1, but upon an enlarged scale.

In machine shop practice it is frequently necessary to provide pilot drillings or "spots" for use in drilling larger holes and this work has either required special machinery or has been a slow, laborious and expensive operation. Again at times, in general machine shop work it becomes necessary to drill very fine and very accurately spaced holes. Unless special machinery be provided such a job requires very accurate planning and a skillful operator, and at best is a slow and expensive operation. In many machine shops such work is done at rather infrequent intervals so that special and expensive machinery is not available. I have provided a very simple and inexpensive con-

struction which every shop can afford to install.

Referring now to the drawings for the details of construction, 1, represents the frame which may take the form of the usual drill press frame and is provided with spaced bearings 2 and 3 in which there is rotatably mounted a shaft or spindle 4. Feathered to the shaft 4 is a pulley 5 so that the desired rotation can be imparted from any suitable source by means of a belt (not shown). The shaft 4 extends through a sleeve 6 and is connected to the tool holder 7 which, in this instance, is provided with the usual chuck 8 for gripping the tool or drill 9. At opposite ends of the sleeve 6 will be found stop rings 10 and 11 which prevent relative longitudinal movement of the shaft 4 and the sleeve 6 whilst permitting rotation of the shaft with in the sleeve. The sleeve 6 is provided with the usual gear rack 12 which meshes with a pinion 13 that is rotatably carried on the shaft 14. In order to enable convenient rotation of the shaft 14 and the pinion 13 the usual hand bar or lever 15 is provided. By the mechanism thus far described drill 9 may be moved to and from the work. For most work the drill of the desired size is merely fixed in the chuck and moved downwardly to 75 drill the hole and retracted.

For accurate work and for "spotting" purposes I have provided a drill guide which, as here shown, takes the form of a bell crank lever having a main arm portion 16 and a 80 secondary arm portion 17. The frame of the drill press is cut away as indicated at 18 to accommodate the bell crank member which is obviously mounted therein as by means of the shaft 18. The operative end 85 of the arm portion 16 is bifurcated as indicated at 19 and is provided with a split bushing 20 and an endless bushing 21. The endless bushing 21 is of a size accurately to fit the drill 9 so that the end of the drill is guided and steadied against any tendency to spring or become disaligned when the drill engages the work. An ordinary bolt 22 is provided to enable convenient clamping of 90 the parts. When a different sized drill is to be used the bushing 21 is removed and another one of the proper size inserted. The bell crank is very accurately formed so that when it is in the full line position shown in Fig. 1 the axis of the bushing 21 will be 100 in perfect alignment with the axis of the drill 9. In order to lock the drill guide in 105 110

this position the arm portion 17 is provided with a hole 23 through which a locking pin 24 passes, the frame of the drill press being provided with suitable holes for the reception of the locking pin 24. When the drill guide is not required the locking pin 24 is removed and the bell crank swung to the dotted line position, shown in Fig. 1, and the locking pin 24 replaced in the hole 25 provided in the arm portion 16. When the bell crank is in the dotted line position the drill press, to all intents and purposes, becomes an ordinary drill press and can be used as conveniently to perform all of the operations to which a drill press is adapted. At the same time it can almost instantly be converted into a machine for very accurately drilling pilot holes or other holes which must be so positioned.

The many advantages of my invention will be apparent to those skilled in the art without further comment.

I claim:

1. In a drilling machine, a frame including a curved portion having a front opening recess therein, a drill holder carried by the frame, a bell crank shaped drill guide member including a short arm and a long arm curved in accordance with the curved portion of the frame, said lever being pivoted at the junction of said arms in the recess in the frame so that the long arm is swingable outwardly to bring a portion thereof in axial alignment with the drill holder and means carried by the curved portion of the frame for holding the drill guide member

firmly in its operative position with respect to the drill holder.

2. In a drilling machine, a frame having a recess therein, a drill holder carried by the frame and a drill guide member pivotally mounted in the recess in the frame and including a short arm and a long arm arranged at an angle to each other, and a drill guide carried at one end of said long arm, said drill guide member being swingable from a position entirely within the recess into a position wherein the long arm is entirely without said recess and a pin arranged in said frame and adapted to engage either arm to lock said drill guide member in either of its positions.

3. In a drilling machine, a frame having a recess therein, a drill holder carried by the frame and a drill guide member pivotally mounted in the recess in the frame, and including relatively short and long angularly disposed arms, each having an opening therein, a drill guide carried at one end of the long arm, said drill guide member being swingable from a position entirely within said recess to a position wherein the long arm is entirely without said recess with the drill guide in alignment with the drill holder, and a pin adapted to be inserted through openings in the recessed portions of the frame and into the opening in either arm to lock said drill guide member in either of its positions.

In testimony whereof, I have hereunto set my hand, this 25th day of September, 1923.

FRANZ K. KRAG.
